CONCRETE BUCKET

Vincent Schiavi, Wilmington, Del.

Application January 24, 1939, Serial No. 252,658

1 Claim. (Cl. 294—69)

This invention relates to an improved bucket for transporting plastic materials.

In the handling of concrete for structural work, it is the common practice to transport the concrete from a mixing station to the required points of delivery by means of a relatively large receptacle, commonly called a bucket, having a suitable bail by which it is suspended from a crane, or the like, and a releasable means for discharging the concrete from the bottom thereof.

Structural concrete work presents variable conditions in the delivery of the concrete, such as relatively restricted spaces between forms; the uniform delivery of the concrete; the rate at which it is delivered; and the amount that is delivered at any required point.

While many different forms of buckets have heretofore been used or proposed for transporting concrete, they have not offered maximum efficiency under the variable conditions presented in concrete work.

It is a primary object of this invention to provide a bucket for transporting concrete or other plastic materials which substantially fulfills the maximum requirements of devices of this kind under all of the many variable conditions of delivery in concrete work.

A further object of the invention is the provision of a bucket for transporting concrete, or the like, which embodies a receptacle having a relatively large receiving top; a restricted discharge bottom and material discharge control means within the receptacle operable externally of the receptacle.

A still further object of the invention is the provision of a concrete bucket embodying a unitary receptacle having a relatively large material receiving portion defined by a vertical wall; a material guiding portion defined by a downwardly converging wall; a restricted delivery portion also defined by a downwardly converging wall, and an externally operable material discharge control valve pivotally supported adjacent the bottom of the material delivery portion.

Yet another aim of the invention is the provision of a bucket for transporting concrete or other plastic material which is of simple, compact, and substantial construction and which is capable of manufacture at relatively little expense.

To the accomplishment of these and related objects as will become apparent as the description proceeds, the invention resides in the construction, combination and arrangement of parts

as will be hereinafter more fully described; illustrated in the accompanying drawing, and pointed out in the appended claim.

For a more complete understanding of the invention, reference will now be made to the accompanying drawing, forming a part of the disclosure, and wherein like characters designate like parts in the different views thereof.

In the drawing:

Fig. 1 is a side elevational view of the improved bucket in a preferred structural embodiment thereof.

Fig. 2 is a vertical sectional view in a plane substantially as indicated by the line 2—2 in Fig. 1, the view indicating the valve in open position 15 by dot and dash lines.

Fig. 3 is a top plan view of the bucket.

Referring now in detail to the drawing, the improved bucket designated in its entirety by the character B is generally of hopper-form and comprises an upper or top portion 10 whose wall is vertical and preferably, though not necessarily, circular in plan; an intermediate or central body portion 11 whose wall converges downwardly and which is of frusto-conical form, and a bottom discharge spout 12.

As indicated in Fig. 1, the portions 10, 11 and 12 are integral, but they (and particularly the spout 12) may be individual parts and connected to each other in any desired manner.

It is to be observed, however, that the one piece integral construction avoids joints and securing means thereby presenting a smooth inner surface for the unobstructed movement of the concrete toward the bottom of the bucket upon being discharged therefrom.

The bucket includes a bail 13 of any suitable or desirable form for transporting of the bucket by a crane or the like. As indicated, the bail consists of a bar of sheet metal having its ends extended through opposite walls of the portion 10 as indicated at 14, said bail having a centrally disposed upward bend 15 for receiving a hook or the like.

A shaft 16 extends diametrically through the opposite walls of the bucket adjacent the junction of the portions 11 and 12 and has its opposite ends rotatably journaled in bearing lugs 17 secured to the exterior wall of the bucket.

The shaft 16 rigidly supports a butterfly valve 18 which normally lies in horizontal balanced position, as indicated in Fig. 2, for supporting the bottom of the concrete mass and permitting discharge thereof through the spout 12 in a manner later described.

A bail-shaped lever 19 has the free ends of its legs 20 fastened to the shaft 16 adjacent the bearing lugs 17, with the horizontal portion 21 serving as a hand grip for rocking the lever in controlling the valve 18. The lever 19 in its normal position wherein the valve 18 is in horizontal closed position, projects obliquely upwardly with its horizontal portion in engagement with the exterior of the bucket wall and is maintained in such position by any suitable retaining means.

The retaining means for the lever as shown comprises a pair of brackets 22 and 23 fixed to the exterior wall of the bucket in sufficiently spaced relation to receive the hand grip portion 21 of the lever therebetween, as is most clearly indicated in Fig. 2. The brackets 22 and 23 have aligned apertures for the removable reception of a pin 24 for holding the lever against downward swinging movement and thereby maintaining the valve 18 in material sustaining position.

The improved bucket as above described in detail substantially satisfies the varied requirements in concrete work in that the relatively large open upper end portion 10 provides for admission of the material without any attendant danger of spilling; the downwardly converging central portion receives the greater portion of the mass of material and aids in the gravitational discharge when the valve is open, and the restricted downwardly converging spout well adapts the bucket for use in discharging concrete in relatively narrow spaces between forms, and the like.

The absence of joints and fastening means provides a smooth inner surface for the unrestricted gravitational discharge of the material. The balanced butterfly valve 18 supports the mass of material above the discharge spout 12 while being transported and by manual manipula-

tion of the lever 19, after release of pin 24, the material may be expeditiously and conveniently discharged in the required amounts and at any desired rate dependent upon the extent of opening of the valve. It is to be particularly noted that the operating means for the valve is wholly externally of the bucket.

The improved bucket is simple and durable in construction and may be made from any desired material of a gauge dependent upon the size of the bucket.

While there is disclosed but a single specific embodiment of the invention, such is to be considered as illustrative only and not restrictive, the scope of the invention being defined in the subjoined claim.

What I claim and desire to secure by U. S. Letters Patent is:

A concrete bucket comprising a unitary body including a relatively large upper portion defined by an annular vertical wall, an intermediate portion defined by a downwardly converging annular wall, and a lower discharge portion defined by a second downwardly converging annular wall; a pair of spaced bearings secured to the bucket at opposed positions, a rotatable shaft extending diametrically through the body at the junction of the intermediate and lower discharge portions and through said bearings, a butterfly valve centrally secured to said shaft within the bucket and normally closing the narrowest part of the intermediate portion, an operating lever including a pair of leg members respectively secured to opposite ends of the shaft outwardly of said bearing members and a hand grip portion between the leg members, a pin removably supported by the outer wall of the body for holding the lever in normal position with the valve closed.

VINCENT SCHIAVI.
